UNITED STATES PATENT OFFICE

156,298

DESIGN FOR A PRESSURE COOKER

Franz Wagner, Chicago, Ill., assignor to Ekco Products Company, Chicago, Ill., a corporation of Illinois

Application January 8, 1949, Serial No. 125

Term of patent 14 years

(Cl. D44—1)

To all whom it may concern:

Be it known that I, Franz Wagner, a citizen of the United States, residing at Chicago, county of Cook, State of Illinois, have invented a new, original, and ornamental Design for a Pressure Cooker, of which the following is a specification, reference being had to the accompanying drawing, forming part thereof.

Fig. 1 is a side elevational view of a pressure cooker, showing my new design.

Fig. 2 is a top view thereof.

Fig. 3 is a side elevational view as the article appears when turned to the right about its upright axis through an arc of 90 degrees relative to its position as shown in Fig. 1.

Fig. 4 is a similar view as the article appears when turned to the left about its upright axis

through an arc of 90 degrees relative to its position as shown in Fig. 1.

I claim:

The ornamental design for a pressure cooker, as shown and described.

FRANZ WAGNER.
